UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

PLATE FINISHING AND TRIMMING MACHINE.

1,129,948.

Specification of Letters Patent.

Patented Mar. 2, 1915.

Application filed January 6, 1911. Serial No. 601,130.

To all whom it may concern:

Be it known that I, HENRY F. BECHMAN, of Battle Creek, in the county of Calhoun and State of Michigan, have invented certain new and useful Improvements in Plate Finishing and Trimming Machines; and I hereby declare that the following is a full, clear, and exact description thereof, reference being had to the accompanying drawings, which form part of this specification.

This invention is a novel machine for finishing tubular stereotype plates such as are used in rotary printing presses of the type shown in Patents Number 867,230 and Number 867,231 granted to my assignee October 1, 1907. And the object of this invention is to provide a novel machine in which such tubular plates can be truly shaved, so as to accurately fit the plate cylinders, and beveled at the ends so as to be of proper length, and thus be finished ready to be immediately placed upon a plate cylinder, after removal from the machine.

The invention consists in the novel construction of parts and combinations of parts in the machine as hereinafter described, and the features for which protection is desired and in which the invention consists are summarized in the appended claims.

In the drawings—Figure 1 is a plan view of the complete plate finishing machine. Fig. 2 is an enlarged right hand end elevation thereof, the base supporting legs being broken away. Fig. 3 is an enlarged longitudinal vertical section of the machine. Fig. 4 is a transverse section on line 4—4, Fig. 1. Fig. 5 is a transverse vertical section on line 5—5, Fig. 1. Fig. 6 is an enlarged detail sectional view of the devices for expanding and locking the plate in the plate holder.

The base or table 1, upon which the operative parts of the machine are mounted, may be of any desired kind. Upon this base and adjacent one end thereof are fixed a pair of axially alined annular bearings 2, in which is rotatably mounted a tubular-plate holder 3 which is in the form of a cylinder and has a gear 3^a on its end adjacent the inner bearing 2, which gear meshes with a driving gear, hereinafter referred to.

Mounted upon the plate-holder 3, intermediate the bearings 2, is an annular collar 3^b (Figs. 1-3-5) which is of a width to fit easily but closely between the bearings 2;

and this collar is provided with a radial slot 3^c through which slot projects a lug 3^d that is secured to the holder 3 by a bolt 3^e, or other suitable means: And upon the collar 3^b, adjacent the lugs 3^d and at one end of the slot 3^c, is a lug 3^f through which is tapped a bolt 3^g; the inner end of said bolt being adapted to contact with lug 3^d; so that by turning bolt 3^g into engagement with lug 3^d the collar 3^b may be shifted slightly rotatorially of the holder 3. The collar 3^b is also provided with laterally projecting lugs 3^h through which extend radially disposed slots in which are placed pins 3ⁱ (Fig. 6) the inner ends of which project into the interior of the plate cylinder 3 through slots 3^j in the holder, said slots 3^j being of sufficient length to permit the desired rotatorial adjustment of the collar 3^b on the holder 3. The pins 3ⁱ may be secured in position by means of bolts 3^k tapped through the lugs 3^h.

Within the holder 3 adjacent the pins 3ⁱ is an abutment or bar 3^l which is slightly thinner than the stereotype plates which are to be finished in the machine, and which is also slightly narrower than the width of the marginal slot between the adjacent ends of this plate (see Figs. 5 and 6). The tubular plates P upon which this machine is designed to operate are of one newspaper-page in area, and are bent or curved into almost complete tubular form, so that such a plate will practically surround the plate cylinder on which it is applied; and in the preferred form of such tubular plates the narrow space or slit between the adjacent ends of the plate corresponds in width to the desired margin between successive impressions taken from such tubular page plate upon a web of paper.

The abutment 3^l extends longitudinally of the plate and may be notched or slotted (as shown at 3° in Fig. 6) to accommodate the inner ends of the pins 3ⁱ. When the plate P is in the holder the abutment 3^l and inner ends of pins 3ⁱ lie within the slot in the plate, and one edge of the slot bears against one edge of the abutment 3^l, and the other edge of the slot in the plate is engaged by the pins 3ⁱ (see Fig. 6).

The gear 3^a of the holder 3 meshes with a pinion 4^a on a shaft 4 journaled in a bearing 4^b attached to the base 1, (Figs. 1 and 2) shaft 4 lying axially parallel with, but

at one end of, the holder 3. The gear 4^a in turn meshes with a pinion 5^a on a shaft 5 journaled in bearings 5^b and 5^c attached to the base 1. Shaft 5 has a pulley 5^d on its outer end which can be belted to any suitable driver; and when shaft 5 is rotated the holder 3 is also rotated in its bearings.

Mounted axially of and extending through the holder 3 is a bar 6 which is supported in brackets 6^a and 6^b attached to base 1, and is preferably provided on its under side with a slot in which is guided a slidable rack bar 6^c (see Figs. 3, 4 and 5). Rack bar 6^c meshes with a pinion 7^a loosely mounted on a transverse shaft 7 journaled in bearings 7^b on the frame adjacent the bracket 6^a; pinion 7^a has a clutch member 7^c on its outer face opposed to a clutch member 7^d slidably keyed to shaft 7, member 7^d has a groove 7^e engaged by a pin 7^f on a lever 7^g, pivoted at 7^h on a bracket 7ⁿ attached to bar 6; and by shifting lever 7^g the clutch members 7^c can be engaged with clutch member 7^d, or disengaged therefrom, so as to cause pinion 7^a to rotate, or cease rotating, at the will of the operator.

The shaft 7 is driven by a worm gear 7ⁱ on its outer end meshing with a worm 4ⁱ on the adjacent end of shaft 4. The rack bar 6^c can be moved in one direction by the power actuated rotation of pinion 7^a. When the clutch members 7^c, 7^d are thrown out of engagement, the bar 6^c can be retracted by any suitable means; preferably by means of a weight 6^e attached to a chain or cord 6^f running over a pulley 6^g mounted in a bracket 6^h attached to the rear end of bar 6, see Fig. 3.

Slidably mounted upon the bar 6 is a tool-holder 8, which is fastened to the rack bar 6^c and is slid along the bar 6 by said rack bar (see Figs. 2, 3 and 5). The holder 8 carries two or more cutters 8^a, which may be secured thereto by screws 8^b, and which are adapted to accurately and truly bore the interior of a tubular plate P secured within and rotated by the holder 3. The tool holder 8 is normally retracted out of the plate holder, but is advanced therethrough at the proper time by the power actuated movement of the rack bar 6^c and is retracted therefrom by the weight actuated movement of the rack bar.

At the outer end of the holder 3 is a cutting and trimming tool 9, which is attached to a slide 9^a mounted in a guide 9^b attached to the base 1; said slide can be reciprocated by means of a hand operated screw 9^c. On the holder 9^a is also mounted a second cutting and trimming tool 9^e; but when cutter 9^e is used, cutter 9 is removed; or shifted back so that it cannot operate upon the tubular plate. The cutter 9 is intended to be used for short, or 7 column, page-plates; while the cutter 9^e is to be used for cutting

long, or 8 column, page-plates. A similar cutter 9^m is mounted adjacent the inner end of the holder 3; being attached to a slide 9ⁿ mounted in a guide 9° attached to base 1; slide 9ⁿ being reciprocated by means of a hand operated screw 9^p.

To remove a finished page plate from the holder, I provide an ejector bar 10, mounted in such position that it can engage the edge of the plate, said bar 10 being guided through keepers 10^a, 10^b, attached to the brackets 6^a, 6^b respectively. The ejector 10 can be operated by a hand lever 10^c pivoted at an intermediate point 10^d to the ejector, and at its inner end to a link 10^e, which in turn is pivoted at 10^f on the casting 6^a.

Operation: The tubular page plates are cast in any suitable apparatus, such as described in my Patent Number 925,268 of June 15, 1909; and after the tool-holder 8 and the cutters 9, 9^e, 9^m are retracted, and the holder 3 stopped, a tubular page plate P is slid endwise into the holder 3, with the casting head on the outer end of the plate, the plate being turned so that its slot moves past abutment 3^l in the plate holder, and said abutment and pins 3^l lie within the slot in the plate, as indicated in Figs. 5 and 6. The operator then turns bolt 3^g so as to cause it to engage lug 3^h and collar 3^b on the holder 3; the holder being practically locked against rotative movement by reason of its engagement with the driving gear; the tendency however when bolt 3^g is tightened, is to turn plate holder 3 in one direction; and the collar 3^b in the opposite direction: As a result the abutment 3^l engages one edge of the slot in the plate P and the pins 3^l engage the other edge of the slot in such plate, and expand the plate forcibly within the plate holder, see Fig. 5, which plate holder is accurately bored on its inner surface to correspond with the desired exterior diameter of the tubular page plate when applied to a plate cylinder ready for printing. In this way the plate P is securely locked in the plate holder and must rotate therewith when motion is imparted to the plate holder from the shaft 5.

As the plate holder rotates the operator shifts lever 7^g so as to engage clutch members 7^c, 7^d and cause pinion 7^a to move rack bar 6^c in a direction to cause tool holder 8 to traverse along bar 6 and through the plate holder and plate. The cutters 8^a are so adjusted that they will accurately dress or shave the interior of the plate P as they move therethrough, so that the plate P will fit accurately upon the plate cylinder when applied thereto. After the cutters 8^a have finished their work the clutch members 7^c, 7^d are disengaged and the weight 6^e will immediately retract the rack bar 6^c and withdraw tool holder 8 from the plate holder. In order to prevent jar when the tool holder

or shaver is retracted, the weight 6^e may be set in a vertical tube 6^a which is open at top and closed at bottom, but has a large opening 6^a a few inches above its bottom, and a very small aperture 6^b at its bottom. The weight 6^e may have a ring or washer 6^r on its lower end adapted to make a close fit in the tube. The parts are so constructed that the weight 6^e will descend rapidly until it passes the opening 6^a and then it is checked by the air confined in the tube which escapes slowly through the aperture 6^b and thus checks the fall of the weight, and the parts are brought to a stop without any shock.

The operator can manipulate the slides 9^a and 9^m, so as to cause cutter 9 (or 9^e) to trim off the head and bevel the outer end of the tubular plate, and the cutter 9^m to bevel the inner end of the plate either during or after the shaving operation. The cutters 9 (or 9^e) and 9^m are then retracted out of the way.

When the rotation of the plate holder 3 is stopped, bolt 3^z is turned so as to cause abutment 3¹ and pins 3⁴ to release the finished plate. Then the operator grasps handle 10^e and moves the ejector rod 10 into the plate holder. The rod 10 preferably has a cross piece or lug 10^z near its inner end which is adapted to engage the edge of the plate while the end of the rod enters the plate, and the cross piece forces the finished tubular plate endwise out of the holder until it can be readily grasped by the operator and removed. When the pins 3⁴ are released to permit the finished plate to be slid out, they are far enough back in slots 3⁰ to allow the next plate to enter. Both the slight spring of the released plate and the twist that the operator naturally gives such plate in withdrawing it by hand serve to thrust the pins 3⁴ back flush with the bar 3¹. Another plate may then be inserted, shaved and trimmed in the manner described.

What I claim is:

1. In a machine for finishing tubular plates, a cylindric plate holder, and means for expanding a tubular-plate within said holder; with cutting tools mounted at opposite ends of the plate holder adapted to trim the ends of the plate and means for reciprocating said cutting tools.
2. In a machine for finishing tubular plates, a cylindric plate-holder, means for securing a tubular-plate therein, a shaver for operating on the tubular-plate within the holder, and means for moving said shaver longitudinally of the holder to shave the tubular-plate; with a cutting tool at each end of the holder adapted to trim the ends of the tubular plate, and means for reciprocating said cutting tools.
3. In a machine for finishing tubular

stereotype plates, a cylindric plate-holder, means for securing a tubular-plate therein, a non-rotatable shaver for operating on the tubular-plate within the holder, and means for moving said shaver longitudinally of the holder during the rotation of the tubular-plate by the holder; with a cutting tool at each end of the holder adapted to trim the ends of the tubular-plate, and manually operable means for reciprocating said cutting tools.

4. In a machine for finishing tubular stereotype plates, a cylindric plate-holder adapted to contain a slotted tubular plate, a collar rotatably mounted on said holder, an abutment within the holder, pins attached to said collar and projecting into said holder adjacent the abutment, said pins and abutment being adapted to engage the opposite edges of the slot in a tubular plate inserted in said holder, and means for turning the collar relative to the holder to cause the abutment and pins to expand the tubular plate.

5. In a machine for finishing tubular stereotype plates, a cylindric plate-holder adapted to contain a slotted tubular plate, an abutment in said holder adapted to engage one edge of a slot in the plate, means in said holder for engaging the opposite edge of the plate, and means for causing said devices and abutment to separate so as to forcibly expand the plate in the holder; with cutters mounted at the ends of the holder and adapted to trim the edges of the plate while held in the holder; and means for shifting said cutters.

6. In a machine for finishing tubular stereotype plates, a cylindric plate holder adapted to contain a slotted tubular plate, an abutment in said holder adapted to engage one edge of a slot in the plate, means in said holder for engaging the opposite edge of the plate, and means for causing said devices and abutment to separate so as to forcibly expand the plate in the holder; and a shaver adapted to traverse the holder and plate; cutters mounted on the frame at the ends of the holder adapted to trim the edges of the plate while held in the holder, and means for shifting said cutters.

7. In a machine for finishing tubular stereotype plates, a cylindric plate holder adapted to contain a slotted tubular plate, a collar rotatably mounted on said holder, an abutment within the holder, pins attached to said collar and projecting into said holder adjacent the abutment, said pins and abutment being adapted to engage the opposite edges of the slot in a tubular plate inserted in said holder; and means for turning the collar relative to the holder to cause the abutment and pins to expand the plate; with a shaver adapted to traverse the holder and plate.

8. In a machine for finishing tubular stereotype plates, a cylindric plate holder adapted to contain a slotted tubular plate, a collar rotatably mounted on said holder, 5 an abutment within the holder, pins attached to said collar and projecting into said holder adjacent the abutment, said pins and abutment being adapted to engage the opposite edges of the slot in a tubular plate inserted in said holder; and means for turning the collar relative to the holder to cause the abutment and pins to expand the plate; with a shaver adapted to traverse the holder and plate; and cutting 10 and trimming tools mounted on the frame at the ends of the holder adapted to trim the edges of the plate while held in the holder.
9. In a machine for finishing tubular stereotype plates, the combination of a cylindric plate holder adapted to contain a slotted tubular plate, a collar adjustably mounted upon said holder, a lug on the holder projecting through a slot in said collar, a bolt tapped through a lug on the 20 collar adapted to engage the lug on the holder; an abutment within the holder adapted to engage one edge of a slot in the plate, and pins attached to said collar and projecting through slots in the holder and 25 adapted to engage the opposite edges of the plate whereby the plate may be expanded and secured within the holder.
10. In a machine for finishing tubular stereotype plates, the combination of a cylindric plate holder adapted to contain a slotted tubular plate, a collar adjustably mounted upon said holder, a lug on the holder projecting through a slot in said collar, a bolt tapped through a lug on the 30 collar adapted to engage the lug on the holder; an abutment within the holder adapted to engage one edge of a slot in the plate, and pins attached to said collar and projecting through slots in the holder and 35 adapted to engage the opposite edges of the slot in the plate whereby the plate may be expanded and secured within the holder; with a shaver adapted to traverse the holder and plate; and cutters mounted at the ends 40 of the holder and adapted to trim the edges of the plate while held in the holder, and means for shifting said cutters.
11. In a machine for finishing a tubular stereotype plate, a rotary cylindric plate holder adapted to contain a tubular plate, means for shaving said plate; and an ejector for removing the finished plate from the holder.
12. In a machine for finishing tubular stereotype plates, a tubular-plate holder, 60 means for expanding a tubular-plate within said holder, and means for shaving the plate; with means for ejecting the finished plate from the holder.
13. In a machine for finishing tubular stereotype plates, a tubular-plate holder, and means for expanding a tubular-plate within said holder; with a slideable bar adapted to eject the plate from the holder, and a lever for operating said ejector bar. 65
14. In combination, a tubular-plate holder, means for expanding a slotted tubular stereotype plate therein, means for rotating said holder and plate, a non-rotatable shaver, and means for reciprocating said 70 shaver through the plate as the latter is rotated; with a plate cutting tool at each end of the holder and manually operable means for independently moving said cutting tools to and from the plate.
15. In combination, a tubular-plate holder, means for rotating said holder, means for securing a slotted tubular stereotype plate therein and expanding it so as to hold its type face in close contact with the 85 inner wall of the holder, a shaver, and means for reciprocating said shaver axially of the holder; and a slideable bar for ejecting the finished plate from the holder.
16. A machine for finishing stereotype 90 plates comprising a rotatable cylinder adapted to contain a single-page slotted tubular-plate, means for securing and expanding such plate in said cylinder, and gearing for rotating said cylinder; with a fixed bar 95 extending axially through said cylinder, a shaver carrying slide on said bar, means for reciprocating said slide on said bar as the cylinder rotates, to cause the shaver to shave the plate; a transversely movable slide adjacent each end of said cylinder, and a cutting and trimming tool carried by each slide and adapted to operate on the plate while the cylinder rotates. 100

In testimony that I claim the foregoing as 105 my own, I affix my signature in presence of two witnesses.

HENRY F. BECHMAN.
